EUGENE L. MESSLER, OF PITTSBURGH, PENNSYLVANIA

SUPPORT FOR HOT TOPS

Application filed July 31, 1931. Serial No. 554,219.

My invention relates to the mounting and use of hot tops on ingot molds during the teeming and solidification of ingots.

In order to obtain to the fullest extent the heat-conserving advantages of a hot top, and to avoid possibility of causing a hanging ingot, it is desirable that a hot top, which has been initially supported on the upper edge of an ingot mold, be permitted to sink 10 into the mold cavity during solidification and contraction of the ingot.

My invention provides for the mounting and accurate positioning of the hot top during teeming; and for the spontaneous release of the hot top during solidification of the ingot metal, so that it floats upon, and sinks with the contraction of, the ingot metal in the mold cavity.

My invention further permits the use of 20 hot tops of such simple contour, and such positioning with respect to the ingot mold and its cavity, that in the majority of instances the hot top is not gripped and cracked by the contracting ingot metal.

25 In the accompanying drawing Figure I is a plan view showing a form of hot top supporting structure for effecting my object; Figure II is a side elevation of the same, indicating the positioning of a hot top with respect thereto; Figure III is a 30 vertical sectional view through an ingot mold and through a hot top mounted thereon in accordance with my invention, showing the position of the hot top immediately

35 after teeming; Figure IV is a similar view showing the position of the hot top in the ingot mold cavity after the hot top supporting means have disintegrated under the temperatures existent during and immediately

40 after teeming; Figure V is a bottom plan view of a slightly modified form of hot top supporting structure; Figure VI is a side elevation of the same; Figure VII is a fragmentary sectional view on an enlarged scale, showing the details of the supporting structure, and illustrating the manner in which a hot top is supported thereon; and Figure 45 VIII is a similar view illustrating a disintegration of the structure sufficient to release

the hot top to sink with the ingot metal in the mold cavity.

Where occurring throughout the figures of the drawing, reference numeral 1 represents an ingot mold, and reference numeral 2 a 55 hot top therefor.

According to my invention, I mount or support the hot top on the ingot mold by means which disintegrate spontaneously under temperatures existing during and immediately after teeming. It may not be said that this disintegration is "slow" at such temperatures. The supporting structure is, however, of such nature that the disintegration is "retarded." The supporting structure thus serves to support the hot top in its mounted position for at least such time as is required to fully teem the ingot. Shortly after teeming it spontaneously disintegrates 60 to release the hot top.

As illustrated, the hot top supporting structure, designated generally by reference numeral 3, comprises primarily a torus or flat ring 4. This flat ring 4 is so proportioned for the size of ingot mold with which it is 75 used, that the outer portion of its width 4a lies upon the upper edge of the ingot mold, and the inner portion 4b of its width extends horizontally inward of the mold cavity.

This flat ring 4 is of a material which 80 burns or otherwise disintegrates under the temperatures encountered. If it is of light gauge steel, the disintegration is by fusion. If, as preferred, it is of fibre board, partially preproofed by compression, or by the inclusion of asbestos or other non-combustible 85 material, the disintegration is by combustion. In either instance the disintegration is retarded in that it does not occur instantly upon subjection of the ring 4 to molten metal 90 at its teeming temperature.

In assembly, the ring 4 is placed upon the upper edge of the ingot mold 1, and a hot top 2 is placed upon the annular region 4b which extends horizontally inward of the 95 mold cavity. Desirably, weight is brought to bear upon the ring portion 4a which lies upon the ingot mold, by placing suitable material, such as a ring of metal, on this portion of the ring.

The hot top 2 is exteriorly of simple, cylindrical contour, and has throughout its height an overall diameter slightly less than the diameter of the upper region in the mold cavity. When the ingot metal is teemed through the hot top and the ingot mold cavity is filled with the metal, the temperature to which the ring is subjected causes its disintegration within a relatively brief period of time. As the inner portion 4b of the horizontal ring 4 disintegrates under the teeming temperature, assisted by the weight of the hot top 2, the hot top is released. Because of the further fact that its diameter is slightly less than the diameter of the ingot mold bore in its upper region, the hot top is thus free to float upon the metal in the mold cavity and to sink in the mold cavity with the metal as it contracts.

As the freedom of the hot top to sink, when released by disintegration of ring portion 4b, is limited only by the contraction of the metal, and the contour of the mold cavity, there is little clamping action of the metal on the hot top. In a relatively great percentage of teemings it is, therefore, possible to remove the hot top from the solidified ingot in condition for subsequent reuse. This is more particularly the case when multiple-piece hot tops are used.

It is highly desirable to attach to flat ring 4 two annuli, each of which performs a two-fold function, and which together define the division between outer ring portion 4a and inner ring portion 4b. Of the two annuli, annulus 5 is in position perpendicular to the under face of ring 4. It is shown as attached to ring 4 by means of foot 5a on the annulus and engaging the inner portion 4b of the ring.

The annulus 5 serves to position the ring with respect to the ingot mold cavity, and also serves to prevent leakage of metal between the ring 4 and the upper edge of the ingot mold during and immediately after teeming.

Annulus 7 is attached to extend perpendicularly upward from ring 4 by means of an outwardly directed foot 7a engaging the outer ring portion 4a. Annulus 7 serves to position the hot top properly with respect to the ingot mold cavity, and also prevents leakage of metal between the lower edge of hot top 2 and the upper face of flat ring 4. If multiple piece hot tops are used, the annulus 7 avoids the necessity of tightly wiring the pieces together.

The modified supporting structure of Figures V and VI is designated generally by reference numeral 8. The modification illustrated in these figures of the drawing resides only in the special contouring of the depending annulus 8a to fit the special contour of the mold cavity. The upwardly extending

annulus 8b may be of simple contour to receive an annulus of similar contour.

It should be understood that the annuli of the supporting structure may, like the flat ring, be made either of slowly combustible material, as for example a partially fire-proofed fibre board, or may be made of a material which will otherwise disintegrate under the temperature conditions, as for example thin gauge steel.

My manner of supporting the hot top on the ingot mold is far more satisfactory than the expedient of suspending hot tops, to be released after the ingot metal has been teemed; or the expedient of inserting wedges or blocks beneath a ledge on the hot top, and removing the blocks or wedges to permit the hot top to sink after teeming.

According to my invention, the sinking of the hot top after teeming is spontaneously effected during the proper time period after teeming; possibility of ingot metal leakage is eliminated; and further the hot top itself is not clamped by the metal as it solidifies, so that in many instances the hot top remains in condition suitable for subsequent reuse.

It should be understood that throughout the specification and claims I do not intend by the terms "ring" and "annulus" to limit these structural elements to a circular contour. In accordance with the contour of the ingot mold and hot top they may be approximately rectangular, or of any other contour conforming to that of the ingot mold and hot top.

I claim as my invention:

1. Means for supporting a hot top on an ingot mold comprising a flat ring retardedly disintegratable at the temperatures existing during the teeming and solidification of an ingot, an annulus attached to the lower face of the ring intermediate its width to extend downwardly in a generally perpendicular direction therefrom, said annulus being flexible to conform closely to the bore wall of an ingot mold cavity to form with the flat ring a seal therein, and an annulus extending upwardly from the opposite face of the ring intermediate its width and constituting a positioning element surrounding the hot top and in co-operation with the flat ring forming a seal at the lower edge of the hot top.

2. Means for supporting a hot top on an ingot mold comprising a flat ring retardedly disintegratable at the temperatures existing during the teeming and solidification of an ingot, an annulus attached to the lower face of the ring intermediate its width to extend downwardly in a generally perpendicular direction therefrom, said annulus being flexible to conform closely to the bore wall of an ingot mold cavity to form with the flat ring a seal therein, and an annulus extending upwardly from the opposite face of the ring constituting a positioning element disposed

inwardly of the outer edge of the ring to position a hot top with its peripheral edge inwardly of the outer edge of the ring and in co-operation with the ring forming a seal at the lower edge of the hot top.

In testimony whereof I have hereunto set my hand.

EUGENE L. MESSLER.
